UNITED STATES PATENT OFFICE.

WILLIAM A. SCHURMANN, OF CHICAGO, ILLINOIS, ASSIGNOR TO W. A. SCHURMANN & CO., INC., OF CHICAGO, ILLINOIS, A CORPORATION OF ILLINOIS.

EGG-CARTON FILLER.

Application filed June 20, 1923. Serial No. 646,516.

This invention relates to containers or receptacles, and more particularly to those employed to hold eggs, such as the egg cartons and fillers in which eggs are ordinarily sold. A carton and filler of this character ordinarily holds a dozen eggs, and is of predetermined or standard size. The cartons when filled are packed closely together and shipped in a way that tends to place a limit 10 on the size of the carton.

Generally stated, the object of the invention is to provide an improved construction and arrangement of the filler, whereby somewhat larger compartments or cells are provided for the eggs, without increasing the size of the carton or box in which the filler and eggs are enclosed.

It is also an object to provide certain details and features of construction and combinations tending to increase the general efficiency and the desirability of an egg carton and filler of this particular character.

To these and other useful ends the invention consists in the matters hereinafter set forth and claimed and shown in the accompanying drawings, in which,—

Fig. 1 is a plan of an egg carton and filler therefor, embodying the principles of the invention, showing the cover and its flap 30 in open position and extended from the back of the box in the plane of the top thereof.

Fig. 2 is a horizontal and longitudinal section on line 2—2 in Fig. 1.

Fig. 3 is a transverse section on line 3—3 in Fig. 1, showing the cover and flap in closed position.

Fig. 4 is a similar transverse section on line 4—4 in Fig. 1.

As thus illustrated, the invention comprises an oblong, rectangular box or carton 1 of suitable height and length and width, having its rear wall provided with a swinging cover 2 having a flap 3 for insertion in the box when the cover is closed. The box 45 or carton may be constructed or formed in any suitable or desired manner, but the flap 3 is preferably long enough to rest upon the bottom of the box when the cover is closed.

The filler comprises two longitudinal walls 50 4 and 5 which are of less height than the box, which are spaced apart in the manner shown, whereby the space between these two walls is at the center of the box. The walls 4 and 5 are connected together by the two 55 transverse walls 6, which are of the same

height as the walls 4 and 5 and which are interlocked therewith in the manner shown in Fig. 3 of the drawings. As the exact form of the interlock is not important, the illustration and the general description 60 thereof will be sufficient. The three transverse walls 7 alternate with the walls 6, in the manner shown, and are of the same height as the box, so that the upper edges of the walls 7 support the cover 2 of the 65 box when the cover is closed. These walls 7 interlock with the two walls 4 and 5 in the manner shown in Fig. 4, this being a common form of interlock for the walls of an egg filler. 70

Thus the square cells or compartments, twelve in number, are each somewhat larger than heretofore, and in each case the cell or compartment is formed in part by the outer wall or walls of the box. Ordinarily, in the 75 common form of egg filler, there are three longitudinal walls and seven transverse walls, so that air spaces are provided all around between the filler and the sides and ends of the box; but with the improved construction herein shown and described, only two longitudinal walls are employed for the filler, and five transverse walls, and the egg cells are formed in part by the walls of the box or carton itself. Thus a considerable saving in material is accomplished, and the reduction in height of the walls 4 and 5 and 6 contributes further to the economy or reduction in the use of materials. 85

Oversized eggs are becoming more common, and the enlargement of the cells of the filler, in the manner explained, takes care of the oversized eggs without in any way necessitating an enlargement of the box or carton itself, for, as shown, the latter is of 95 exactly the same size as those previously employed. Of course, in actual practice, the carton and filler are somewhat larger than they are shown in the drawings. In practice, these egg cartons or boxes are approximately three and three-quarters inches in width, one and a quarter inch in height and about ten inches or a little over long, these being approximately the standard dimensions for the ordinary egg 100 box or carton in which eggs are sold to the consumer by the groceries or retail dealers. But with the construction shown and described, the egg cells are somewhat larger than heretofore. 105

Thus it will be seen that the walls 4 and 5 are of less height than the cells, which means that their height is less than the distance between the top and bottom of the box, or that they are less in height than the eggs in the filler; and this is also true of the transverse walls 6, but the alternate walls 7 are higher and extend from top to bottom of the box.

It will be seen that the space between the walls 4 and 5 is less than egg size, so that the row of open top air spaces formed by the transverse partitions or walls is not as wide as either row of egg cells. The two rows of eggs are held apart by an air cushion, so to speak, and the two rows are separated by a sub-divided space which is considerably less in width than the width of the egg cells. All of the transverse walls 6 and 7 have straight upper edges, and the longitudinal walls 4 and 5 have practically straight upper edges, although in the case of longitudinal walls 4 and 5, their straight upper edges are broken at intervals by the notches shown. The alternate transverse walls 7 are as high as the cells, but the intermediate walls 6 are of less height than the cells, and the walls 6, preferably, have their upper edges flush with the upper edges of the walls 4 and 5, as shown.

Thus it will be seen that the eggs are each cushioned at its inner side only, instead of at the outer side. Ordinarily, in the marketing of eggs in two rows in a carton of standard width, the filler is constructed to form two parallel rows of cells, without any cushioning spaces between the two rows, but such fillers have projecting end portions of the transverse walls, which space the sides of the carton a distance from the sides of the filler, so that each egg under such circumstances is cushioned at its outer side. However, with the construction shown and described, which is illustrative of the invention, the cushioning is left off at the outer sides of the two rows of eggs, and is instead interposed between the two rows of eggs, whereby the egg cells can be somewhat larger to accommodate larger eggs, but without enlarging the box or carton, and without leaving the eggs uncushioned—that is to say, notwithstanding the enlarging of the cells to accommodate larger eggs, the box or carton is of standard width and length,

and the eggs are still cushioned in a manner to prevent breakage thereof.

What I claim as my invention is:—

1. An egg carton and filler therefor comprising longitudinal filler walls having straight upper edges formed with notches therein, relatively high and low transverse filler walls having straight upper and lower edges, the lower edges having notches to engage the notches of said longitudinal walls, the low transverse walls being the same in height as the longitudinal walls, a carton bottom wall supporting the filler, front and rear and end carton walls embracing the filler, and a carton top wall resting on said high walls and thereby spaced a distance above said longitudinal and low walls, the high walls being greater in number than and alternating with the low walls to form two longitudinal rows of square egg cells and to support said top wall against downward pressure on the eggs, and whereby the greater portion of said filler is of less height than the eggs to reduce the use of material in production and also render the filler less conspicuous when the carton is opened to display the eggs.

2. A structure as specified in claim 1, said longitudinal walls being spaced apart a distance less than the width of the cells, between the two longitudinal rows, and said front and rear and end walls forming the outer walls of said cells.

3. An egg carton of ordinary dozen-egg size and form and a one dozen egg filler therefor comprising longitudinal and transverse filler walls forming two longitudinal rows of square egg cells, with six square cells in each row, and the longitudinal walls spaced apart a distance less than the width of the cells, between the two longitudinal rows, to form cushion air cells between the two six-egg rows of cells, carton walls forming the outer side walls of said cells, whereby to reduce the material in the filler without decreasing the capacity thereof, and without changing the size or form of the carton, and carton walls forming the top and bottom of the cells, whereby the eggs in each row are uncushioned at their outer sides but are cushioned between the two rows.

WILLIAM A. SCHURMANN.
